UNITED STATES PATENT OFFICE.

LA VERNE W. NOYES, OF CHICAGO, ILLINOIS.

SELF-BINDING HARVESTER.

SPECIFICATION forming part of Letters Patent No. 392,747, dated November 13, 1888.

Application filed July 23, 1887. Serial No. 245,055. (No model.)

To all whom it may concern:

Be it known that I, LAVERNE W. NOYES, a citizen of the United States, residing at Chicago, in the county of Cook and State of Illinois, have invented certain new and useful Improvements in Self - Binding Harvesters, which are described and fully set forth in the following specification, reference being had to the accompanying drawings, forming part thereof, wherein—

Figure 1 is a plan. Fig. 2 is a rear elevation. Fig. 3 is a detail rear elevation of the discharging mechanism in the process of ejecting the bundle through the trap-gate. Fig. 4 is a detail elevation of some of the same parts shown in Fig. 3, the position being that at which the discharger is being tripped into operative position. Fig. 5 is a detail elevation of the compressor and connected and operating mechanism, the position being that just preceding the instant of greatest compression. Fig. 6 is a detail elevation of the same parts shown in Fig. 5, the position being that at which the discharger is tripping the clutch-dog 25 to disengage the compressor from the needle rock-shaft. Fig. 7 is a detail elevation of the same parts at the instant the compressor is falling out of the path of the bundle to allow its discharge. Figs. 8 and 9 are details of the 30 locking - dog in positions corresponding to those of Figs. 5 and 6. Fig. 10 is an inner side elevation of parts on the binder-mechanism driving-shaft, principally designed to show the manner of securing the discharger-cams. Fig. 11 is a section through $x x$, Fig. 35. Fig. 12 is a sectional elevation of the compressor and frame, the section being at the line $y y$ on Fig. 7. Fig. 13 is a detail elevation of a modification of the bundle-receiving trap-gate. Fig. 14 is an elevation of the compressor-frame detached from binder-frame. Fig. 15 is a plan of the extensible compressor-link comprising its spring and a housing which forms a stop for one end of it.

The construction of the general frame-work of the machine, the devices for raising and lowering and tilting and the gearing for communicating the driving-power to the conveyer and binder, although in part appearing in the drawings, constitute no part of this invention and will be referred to only in so far as may be necessary or convenient in describing the location of those parts with which the invention to be claimed is directly concerned. In general it

may be stated that the frame which carries the 55 platform and sickle and conveyer is the same as that which carries the binder, and may be made adjustable as to elevation and inclination or "tilt" in any well-known way. Parts of this frame not otherwise specifically mentioned or lettered, wherever appearing in the drawings, are lettered A. Specific parts having relation to this invention and rigid with said frame as a part or adjunct thereof are indicated by the letter A with an exponent, except the binder-frame proper, which, although it may be rigid with the platform-frame, is treated as an independent structure, and with its parts and rigid adjuncts is denoted by the letter B and B with an exponent.

The conveying and packing mechanisms are denoted by the letter C, applied to all parts thereof not specifically described, and all specific parts are indicated by the letter C with an exponent.

The several parts of the binder mechanism are specifically lettered as hereinafter indicated.

D is the drive-wheel, which communicates power in the usual manner to the driving-train, of which the first wheel visible in the drawings is the beveled gear-wheel E, which is clutched to the shaft of the main driving-pinion, which shaft is journaled in the gear-bracket A' on the platform-frame. Said gear-wheel E drives the beveled gear-wheel E', whose shaft e' is journaled suitably on the platform-frame, and has the spur-gear E'', which meshes with the gear-wheel C' on the cranked shaft c', which is also journaled on the platform-frame, and by means of its double cranks c¹⁰ c¹⁰ actuates the reciprocating feed-bars C'', which constitute part of the conveying mechanism of the platform-conveyer. A similarly-cranned shaft, c³, at the grain end of the platform is rotated by the feed-bars C'', part of the cranks c¹⁰ being ninety degrees from the remainder, so that there is no dead-center. At the forward end of the shaft c' there is fixed a roller which drives the endless belt C³, which at the grain end passes around the roller c³⁰, which may be either loose or fast on the shaft c', but is preferably loose, since it may be desirable to give the belt a greater or less speed than the feed-bars C'', which may be done by making the driving-roller on the shaft c' larger or smaller, which would necessitate a loose roller on the shaft c'. At the stubble end the

feed-bars C² are provided with inclined extensions C²⁰, which protrude through the binder-deck approach and operate as packers. The intervals between the bars C² in the platform 5 are filled with strips of fixed floor; or, in other words, the feed-bars operate through slots in the platform in the usual manner of such conveying devices.

The binder-driving mechanism, including 10 the tripping and clutching devices, may be of any well-known construction. They are not shown in detail. The main binder gear-wheel F, however, is driven by a train deriving power in any manner from the shaft e', and the needle rock-shaft R is actuated in the customary manner by a link, R', from the wrist-pin f¹⁰ on said gear-wheel to a crank-arm, R², on said rock-shaft.

The peculiarities of this invention are found 20 in the dischargers and their operating mechanism, the compressor and its operating mechanism, and especially in the relation of both said elements to the form of the deck and breast plate, and to a certain auxiliary—viz., the 25 trap-gate K—which will be hereinafter specifically described.

The shaft f of the binder gear-wheel F is journaled in the arm B' of the binder-frame, and near its rear end it carries the knotter- 30 actuating cam-wheel F', having the usual functions and position. Adjacent to said cam-wheel the knotter-frame is hung on said shaft, as is usual, and is extended grainward and obtains further support on the arm B² of the binder-frame, which is extended horizontally rearward from the binder-gear standard B³. From the knotter-frame are extended arms which terminate in the discharger-controlling cams G G, which are pierced for the shaft f and are 40 situated about said shaft, one forward of the knotter-frame and the other rearward of the knotter-actuating cam-wheel, and adjacent to them, respectively, are the discharger-actuating arms G' G', which are so secured on said shaft f as to be revolved thereby, the forward one in front of its cam and the rear one rearward of its cam, and to the ends of said arms G' G' are hinged the dischargers proper, G² G², though, functionally considered, the two parts 45 G' and G² together make up a folding or collapsing discharger.

The dischargers G² have an arm, G²⁰, setting off from near the pivot at nearly a right angle to the direction of the bundle-actuating arm, 55 and said arm G²⁰ has an abutment in the form of an anti-friction roll, g²⁰, which engages and travels upon the periphery of the cam G, and while passing over the concentric part g of the cam G holds the bundle-actuating arm G² extended, so as to engage the bundle, and when 60 it runs off said concentric part at the point g', as shown in Fig. 2, and drops into the cut-away part g², it allows the said arm G² to collapse and withdraw from underneath the bundle. For the purpose of tripping the dis-charge-arm again into operative position, another abutment, g²¹, is provided, which collides

with the corner g³ of the cam after the arm G' has carried the discharger over the shaft and causes the discharger G² to swing up into such 70 position that the cam-roll g²⁰ again rests on the track and holds the arm extended while it passes over the concentric portion. Said concentric portion g is so situated as to keep the discharger extended while it is passing through 75 the lower and next succeeding quarters of its revolution—that is, while it moves through the locality of binding stubbleward and thence upward—until it stands projecting upward and stubbleward, as seen in Fig. 2. The entire 80 construction is therefore such as to remove the bundle upward from the position in which it is bound, first carrying sufficiently stubbleward to get it clear of the knotter. To facilitate this mode of discharge, the breast-plate B⁴ 85 and the binder-deck B⁵ are both extended from the locality of binding in a direction and to an extent corresponding to the movement of the discharger, so that said breast-plate and deck terminate upwardly on the stubbleward side 90 of the knotter and form between them a guiding channel or chute for the bundle.

In order to prevent the bundle from falling back when the dischargers withdraw from beneath it, I provide the trap-gates composed of 95 the spring or pivoted arms K K K, which are supported by the bar L, which forms a rim at the upper edge of the upwardly-extended deck and extend grainward across the path of the bundle as it is carried upward between the 100 extensions of the deck and breast-plate. Said arms have the slanting portion K' from their inner or grainward ends extending downward and stubbleward to the stubbleward side of the passage-way. This slanting portion receives 105 the pressure of the bundle as it is moved upward and causes the gate to swing stubbleward about the lower end of said slanting portion, which is the pivotal point, an arm, K², being extended downward from the bar L to afford 110 such pivotal support. I find it most convenient to make this gate, including all the parts K, K', and K², of one piece of metal rod, which is secured to the bar L and extends downward close to the deck-extension, and at the pivotal point is coiled to form a spring-knee, k, which is in effect a pivot, and thence extends obliquely upward and grainward to the proper height, and is then bent stubbleward and hooked over the bar L, the last portion being 120 curved about the pivot. I consider this form the equivalent of that shown in Fig. 13, the only difference being that in one form the gate is caused to return under the bundle by the action of its spring-knee k and in the other the 125 same movement is produced by gravity.

It will be observed that all the mechanism and other parts concerned in binding and discharging the bundle thus far described are located grainward of the drive-wheel, and that 130 the bundle is ejected upward from the locality of binding between the knotter and the drive-wheel. This arrangement so compacts the mechanism that the compressor and its actu-

ating parts are necessarily operated without employing any parts projecting any distance stubleward of the deck-extension upward or occupying much space below the deck. Further, in view of the form of the deck, which curves upward to form the upward discharge-chute, the movement of the compressor toward the bundle is almost necessarily in a similar curve. I therefore construct the compressor and its operating mechanism as follows: Upon the needle rock-shaft is supported the compressor-frame M, which is steadied by the engagement of its inner end in a groove in the upper edge of the approach to the deck, as seen in Fig. 2. Said frame extends from the vicinity of the needle rock-shaft toward the wheel, curving upward, following the form of the deck at that part. It has the slot m below the deck, following the same course to the point m', where it makes an abrupt turn downward in a short curve about a point in the main course of the slot located a few inches grainward of said turn.

The compressor has an arm or tail which has two abutments provided with anti-friction rolls n' n², which engage in the slot m, which thus becomes a guiding-track for the compressor. The radius of the curved recess portion m² of the slot m is equal to the distance from center to center of the two anti-friction rolls. To actuate this compressor along this guiding-track, I provide mechanism, as follows: On the needle rock-shaft is loosely held the sector gear N³, and pivoted to its face is the dog N⁴, which has the spur n⁴, adapted to engage with the shoulder or notch N¹⁰ on the needle-hub, or, as illustrated, on a removable plate fastened to the needle-hub, for the purpose of adjustment, as hereinafter explained. When the dog is engaged in said shoulder, the needle carries the sector-gear N³ with it while it moves up to encircle the bundle. Upon a bracket-arm of the compressor-frame is journaled the sector-gear N⁵, meshing with and actuated by the sector-gear N³, and said sector-gear is extended to constitute a lever, N⁶, which is connected by a link, N⁷, with the compressor N, the connection being made at the axis of the anti-friction roll n². Said link comprises parts N⁸ and N⁹ and the spring N¹⁰, being an extensible link, the spring tending to resist the extension according to a familiar construction of compressor-links. The dog N⁴ has an arm, N¹¹, which extends in such direction that when the needle is nearly at the limit of its upward movement it stands up toward the upper binder-frame arm and has an offset or abutment, n¹², which at that position is in the path of the rear discharger, so that said discharger, striking said abutment, disengages the dog from the needle-hub and leaves the compressor free from any actuation by the needle. For the purpose of adjusting the point at which this disengagement occurs, the spur n⁴ is made of a separate piece secured by a screw in as many different positions as there are screw-holes through the segmental flange

prolongation n¹⁴ of said spur. For the purpose of adjusting the position at which the compressor mechanism becomes engaged with the needle rock-shaft and determining the degree of compression which the bundle receives, the shoulder N¹⁰ on the needle-hub is also made in a separate piece from said hub and adjustably secured thereto in a manner similar to the securement of the spur n⁴ to the dog N⁴, as before described.

The operation of this mechanism may be described as follows: The grain falling upon the platform is fed by the conveyer in an obvious manner toward the binder, and by the packer-extensions of the conveyer feed-bars is packed in the usual manner on the binder-deck until, by the operation of familiar forms of tripping and clutching mechanism, (not shown,) the binder is brought into action and the needle rises through the deck and carries the cord around the bundle, and, by means of the shoulder N¹⁰, engaging the dog N⁴, the compressor-actuating mechanism is operated and the compressor is drawn along its curved track toward the bundle. At proper time the discharger reaches a position at which its abutment g²¹ trips over the corner g³ of the cam G, and the discharger is turned down into operative position, passing successively through the positions shown in Fig. 4 and Fig. 5, at which latter position it is just about to engage the dog N⁴, the compression being at this stage complete and the bundle ready to be ejected. The next instant it reaches the position shown in Fig. 6, wherein the dog N⁴ is disengaged from the needle rock-shaft, as more fully seen in Fig. 9, and the reaction of the compressor-spring N¹⁰ has caused a partial reverse revolution of the segment-gears N³ and N⁵ and has caused the dog N⁴ to pass over the shoulder N¹⁰. The continued movement of the discharger presses the bundle against the compressor, which, being now freed from all other actuation and restraint, travels up its inclined curved track, and, by means of the link N⁶ N⁷, attached to the lever arm N⁶, rotates the sector-gear N⁵, and thereby the sector-gear N³, until the parts are in the position shown in Fig. 7, the dog N⁴ having been carried clear of the discharger and by its weight having tipped over so that its tooth or spur n⁴ rests on the edge of the piece having the shoulder N¹⁰, and the abutment n¹² on the compressor having reached the recess m² in the track or slot m. The next instant the said abutment has entered the recess, the compressor turning on abutment n² as a fulcrum and reaching the position shown in Figs. 2 and 3, where it no longer offers any opposition to the further upward passage of the bundle. The discharger, continuing its revolution, presses the bundle upward against the trap-gate, the slanting arm K' thereof receiving the pressure, and said gate yields by folding or turning about the pivotal point at the lower end of said slanting arm, and the bundle passes up to the position shown in Fig. 2, when the trap-gate returns underneath the bundle

and is in position to support it, while the dis-
charger, whose abutment g^2 has now reached
the end of the concentric part of the cam G,
as it is further revolved, falls into the cut-
away portion g^3 , and the discharger withdraws
longitudinally from underneath the bundle,
leaving it on the trap-gate, while the discharger
reaches the initial position of rest. The
bundle is now fully ejected from the binder—that
is, from the locality of binding—and it may be
dropped to the ground in any convenient man-
ner. Suitable guides (shown and lettered W
W in Fig. 2) may constitute a chute over the
wheel, and successive bundles will push pre-
ceding ones along such chute and cause them
to fall.

I do not in this application make claims for
the combination, with the binder, of the bun-
dle-carrier located above it, nor for the plat-
form-conveying mechanism, nor the combina-
tions thereof with the packers and abutting
devices shown in the drawings, because I have
claimed these features in my pending applica-
tions, Serial Nos. 245,054, filed simultaneously
herewith, and 265,140, filed February 24, 1888.

I claim—

1. In a self-binding harvester, in combina-
tion with the discharger revolved outward and
upward about an axis located above the lo-
cality of binding to carry the bundle upward,
a trap-gate located in the upward path of the
bundle and yielding out of said path upon be-
ing pressed from beneath, substantially as set
forth.

2. In a self-binding harvester, in combina-
tion with the discharger revolved upward and
outward about an axis located above the lo-
cality of binding to carry the bundle upward,
and a guard, as the extension of the deck, to
keep the bundle on the discharger while it re-
volves upward, and a trap-gate located in the
upward path of the bundle and yielding out
of that path upon being pressed from below,
substantially as set forth.

3. In combination with the binder-deck, the
compressor-frame having a track to guide the
compressor, said compressor having two abut-
ments resting on said track, said track having
a recess at the farther end, into which one
of the abutments of the compressor falls, caus-
ing the compressor to turn on the other to
clear the path for the discharge of the bundle,
substantially as set forth.

4. In combination with the binder deck, the
compressor-frame having a track to guide the
compressor, said compressor actuated in one
direction by suitable connection with the nee-
dle rock-shaft and in the other direction by
the pressure of the bundle derived from the
discharger, and having two abutments resting
on the track in the compressor-frame, said
track having a recess at the end toward which
the bundle moves the compressor, into which
one of the abutments falls, causing the com-
pressor to tilt over the other abutment to clear
the path for the bundle's discharge, substan-
tially as set forth.

5. In combination with the binder-deck, the
compressor-frame having a guiding-track cor-
responding in vertical configuration to the 7c
portion of the deck toward the discharge side,
the compressor supported on such track, a le-
ver fulcrumed on the frame and a link there-
from to the compressor, suitable locking-dog
to connect the lever to the needle rock-shaft, 75
and an arm actuated by the binder-mechan-
ism driving-shaft engaging a suitable projec-
tion from the locking-dog to disengage the
compressor actuating lever from the needle
rock-shaft.

6. In combination, substantially as set forth,
the needle rock-shaft, compressor, compressor-
actuating lever, and the locking-dog thereon,
which connects such lever to the needle rock-
shaft, and the discharger, the locking-dog hav-
ing an arm extending into the path of the dis-
charger, whereby the latter engages the dog
and disengages the same, and thereby the com-
pressor, from the needle rock-shaft when the
discharger commences to eject the bundle. 92

7. In combination with the binder-frame and
needle, the fixed compressor-frame having a
track which supports and guides the com-
pressor, the compressor supported and guided
on such frame, suitable connections from the 95
compressor to the needle rock-shaft, whereby
the latter draws the former along the track to-
ward the bundle, a locking-dog which forms
part of the connection from the needle rock-
shaft to the compressor, having an arm extend-
ing into the path of the discharger, and the
discharger operating above the deck and en-
gaging said locking-dog extension to unlock
the compressor from the needle rock-shaft to
permit it to yield to the discharge movement 105
of the bundle, substantially as set forth.

8. In combination with the binder-frame and
the needle, the fixed compressor-frame having
a track which supports and guides the com-
pressor, the compressor supported and guided
on said track by means of two abutments on
the former, which engage said track, suitable
connection from the needle rock-shaft to the
compressor, whereby the latter draws the
former along the track toward the bundle, a 115
locking-dog which forms part of the connec-
tion from the needle rock-shaft to the com-
pressor having an arm extending into the path
of the discharger, the discharger operating
above the deck and engaging said locking-dog
extension to unlock the compressor from the
needle rock-shaft and permit it to yield to the
discharge movement of the bundle, the com-
pressor-track having a recess at the farther
end, into which one of the compressor-abut-
ments may fall to cause the compressor to
tilt over the other to clear the path for the
discharge of the bundle, substantially as set
forth. 125
